UNITED STATES PATENT OFFICE.

LOUIS KOSSUTH JOHNSON AND ABBOT AUGUSTUS LOW, OF NEW YORK, N. Y.,
ASSIGNORS TO THE ALDEN TYPE MACHINE COMPANY, OF SAME PLACE.

TYPE-CONTAINING CHANNEL.

SPECIFICATION forming part of Letters Patent No. 634,214, dated October 3, 1899.

Application filed June 22, 1896. Serial No. 596,372. (No model.)

To all whom it may concern:

Be it known that we, LOUIS KOSSUTH JOHNSON and ABBOT AUGUSTUS LOW, citizens of the United States, residing in the city of New York, (Brooklyn,) in the county of Kings and State of New York, have invented certain new and useful Improvements in Type-Containing Channels, of which the following is a specification sufficient to enable others skilled in the art to which the invention appertains to make and use the same.

Our invention relates to type-containing channels designed for use in connection with the form of type-case set forth in our application for patent, Serial No. 602,136, filed August 8, 1896; and the invention consists in the special construction and arrangement of parts hereinafter described and claimed.

In the accompanying drawings, Figure 1 is an elevation of the right-hand side of our improved channel; Fig. 2, a front elevation of the same adjusted to the narrowest width; Fig. 3, a top view of Fig. 2; Fig. 4, a front elevation adjusted to the fullest width; Fig. 5, a top view of Fig. 4. Fig. 6 is a longitudinal section on plane of line 6 6, Fig. 1. Fig. 7 is an elevation of the inner side of the left-hand channel-wall. Fig. 8 is a rear view of the same. Fig. 9 is a rear view of the right-hand wall; Fig. 10, a front view of the same. Fig. 11 is a top view of the left-hand side wall; Fig. 12, a similar view of the right-hand side wall.

The channel is made in two parts A and B, each constituting a side wall and a part of the spine. The rear flanges *a b*, which constitute the spine, are formed upon the opposed inner surfaces of the plates or side walls A B and are preferably of equal thickness, each representing one-half the width of the spine when the parts are adjusted for the narrowest types, as illustrated in Figs. 2 and 3. The lower end of one side wall is formed with the laterally-projecting type-floor *c*, extending across the channel and under the lower end of the opposite side wall. This type-platform *c* is of a width sufficient to afford a support for the widest types when the parts are adjusted with relation thereto. The type-platform *c* may obviously be formed on either one or the other of the side walls A B. The

portion of the spine on one side plate ends a considerable distance above the position of the type-floor *c* in order to leave the space or slot *d* for the passage of the type-forwarder 55 when the channel is inserted in the type-setting apparatus. The separation or adjustment of the side walls of the channel with relation to each other is effected by means of screws *s*, by which the portions of the spine 60 are held together, washers *w* being interposed between the spines *a b* when it is desired to widen the channel.

What we claim as our invention, and desire to secure by Letters Patent, is— 65

1. As an article of manufacture a type-containing channel consisting of the side walls A, B, having the flanges *a b*, formed with female screw-threads for the reception of the headless coupling-screws *s*, and said coupling- 70 screws *s*, the whole arranged and operating substantially in the manner and for the purpose described.

2. As an article of manufacture a type-containing channel consisting of side plates each 75 formed with a portion of the common spine and with female screw-threads for engaging with male screws, one side plate being formed at one end with a transverse type-supporting shoulder or flange of a width equal to the 80 maximum width of the channel, and screws for securing the parts rigidly together substantially in the manner and for the purpose described.

3. As an article of manufacture a type-containing channel consisting of side plates each formed with a portion of the common spine and with female screw-threads for engagement with male screws, one side plate being formed at one end with a transverse type-supporting shoulder or flange of a width equal to the 90 maximum width of the channel, spacing washers interposed between the opposed portions of the spine, and screws for securing the parts rigidly together, substantially in the 95 manner and for the purpose described.

4. As an article of manufacture a type-containing channel consisting of side plates each formed with a portion of the common spine and with female screw-threads for engagement with male screws, one side plate being 100 formed at one end with a transverse type-sup-

porting shoulder or flange of a width equal to the maximum width of the channel, the portion of the spine on said side plate ending a sufficient distance above said transverse type-
5 support to form a slot for the passage of the pusher when the parts of the channel are united, and screws for securing the parts rig-

idly together substantially in the manner and for the purpose described.

LOUIS KOSSUTH JOHNSON.
ABBOT AUGUSTUS LOW.
